[57] CLAIM

The ornamental design for a shoe upper, as shown and described.

DESCRIPTION

FIG. 1 is a right side elevational view of the shoe upper according to my new design;

FIG. 2 is a left side elevational view thereof;

FIG. 3 is a front elevational view;

FIG. 4 is a rear elevational view thereof; and,

FIG. 5 is a top plan view thereof.

The broken line showing of a shoe sole is for illustrative purposes only and forms no part of the claimed design.

The part of the underside of the design, not shown, is plain and unornamented.
